UNITED STATES PATENT OFFICE.

JOHN A. MERLEY, OF CANTON, OHIO.

DESIGN FOR A BUILDING-BLOCK.

SPECIFICATION forming part of Design No. 23,063, dated February 13, 1894.

Application filed January 19, 1894. Serial No. 497,445. Term of patent 14 years.

To all whom it may concern:

Be it known that I, JOHN A. MERLEY, a citizen of the United States, and a resident of Canton, county of Stark, State of Ohio, have 5 invented and produced a new Design for Building-Blocks, of which the following is a full, clear, and exact description, reference being had to the accompanying drawings, making part of this specification.

10 My invention relates to a design for a hollow building block.

In the drawings, Figure 1, is a perspective view of the block, and Fig. 2, is a longitudinal vertical sectional of the same.

15 A, denotes the block which is rectangular in form and which is provided at one end with a reduced rectangular tenon a. The face of the block has its four edges beveled

as shown at b thus giving to the face c a panel like appearance.

The leading feature of my design, is the hollow block of rectangular form having at one end a reduced rectangular extension and having the edges of its face beveled.

Having thus described my invention, I 25 claim—

The design for a building block herein shown and described.

In testimony whereof I have hereunto set my hand this 20th day of December, A. D. 30 1893.

JOHN A. MERLEY.

Witnesses:

W. K. MILLER,
BURT A. MILLER.
